CLAIM

The ornamental design for a low profile splash guard for gutter as shown and described.

DESCRIPTION

FIG. 1 is an isometric view of a low profile splash guard for gutter.

FIG. 2 is an obverse isometric view of the low profile splash guard for gutter of FIG. 1.

FIG. 3 is a left side elevation view of the low profile splash guard for gutter of FIG. 1.

FIG. 4 is a right side elevation view of the low profile splash guard for gutter of FIG. 1.

FIG. 5 is a top plan view of the low profile splash guard for gutter of FIG. 1.

FIG. 6 is a bottom plan view of the low profile splash guard for gutter of FIG. 1.

FIG. 7 is a rear elevation view of the low profile splash guard for gutter of FIG. 1.

FIG. 8 is a front elevation view of the low profile splash guard for gutter of FIG. 1; and,

FIG. 9 is another isometric view of the low profile splash guard for gutter of FIG. 1.

Portions of FIGS. 1 through 9 are shown in dash-dot-dash broken lines that illustrate the boundary of the claimed design, which forms no part thereof. The phantom lines in FIG. 9 illustrate environmental subject matter that forms no part of the claimed design. The drawings are shaded to indicate contrasting surfaces.

1 Claim, 7 Drawing Sheets
